[57] CLAIM

The ornamental design for a deployable monitor, as shown and described.

DESCRIPTION

FIG. 1 is an isometric view of a deployable monitor constructed in accordance with the present invention, the monitor being shown in a deployed orientation;
FIG. 2 is a front elevation view thereof;
FIG. 3 is a rear elevation view thereof;
FIG. 4 is a bottom view thereof;
FIG. 5 is a top view thereof;
FIG. 6 is a right-side view thereof, the left-side view being a mirror image thereof; and,
FIG. 7 is a right-side view similar to that of FIG. 6, but with the monitor in a stowed orientation.
